CLAIM

The ornamental design for an infant tote coat, as shown and described.

DESCRIPTION

FIG. 1 is a top front perspective view of an infant tote coat showing our new design;
FIG. 2 is a bottom front perspective view thereof;
FIG. 3 is a top rear perspective view thereof;
FIG. 4 is a bottom rear perspective view thereof;
FIG. 5 is a front elevational view thereof;
FIG. 6 is a rear elevational view thereof;
FIG. 7 is a top plan view thereof;
FIG. 8 is a bottom plan view thereof;
FIG. 9 is a right elevational view thereof;
FIG. 10 is a left elevational view thereof;
FIG. 11 is a magnified view of a bow fastener shown in FIG. 5;
FIG. 12 is a magnified view of a side opening in FIG. 5; and,
FIG. 13 is a magnified view of a ring fastener in FIG. 5.
The broken lines shown in the drawings represent the boundaries of the claim and form no part of the claimed design.
